UNITED STATES PATENT OFFICE.

ELEAZER KEMPSHALL, OF BOSTON, MASSACHUSETTS.

PLAYING-BALL.

SPECIFICATION forming part of Letters Patent No. 714,917, dated December 2, 1902.

Application filed October 11, 1902. Serial No. 126,870. (No model.)

To all whom it may concern:

Be it known that I, ELEAZER KEMPSHALL, manufacturer, a citizen of the United States of America, residing at 41 High street, in the city 5 of Boston, in the county of Suffolk and State of Massachusetts, have invented certain new and useful Improvements in Playing-Balls, of which the following is a specification.

The present invention has for its object to 10 intensify the resiliency of the ball when given a hard blow without materially impairing the solidity that the ball possesses when struck lightly and on alighting.

According to this invention I provide the 15 ball with a pneumatic center piece composed of india-rubber or other suitable material. Upon this center piece I may wind the highly-tensioned elastic material prior to applying the external casing or cover. In some cases 20 in order to prevent said pneumatic center piece from being displaced from the true center of the ball by any want of symmetry in the winding I may, after said winding has proceeded to a certain extent, inclose it in a 25 hard, but more or less resilient, shell—for instance, of celluloid—and continue the winding around the exterior thereof. If desired, two or more of such shells may be employed.

In order that the said invention may be 30 clearly understood and readily carried into effect, I will now proceed to describe the same more fully with reference to the accompanying drawings, in which—

Figure 1 is a section of the pneumatic ball 35 with its windings of highly-tensioned material having embedded therein the aforesaid shells or cups of celluloid. Fig. 2 is a separate view of the center piece, and Fig. 3 shows the inner part of the ball in a partially-wound condition.

A is the external cover of the casing containing the elastic material *aa*. D is the hollow full-size center piece upon which said material is wound, and *c* the aforesaid shell 45 that is embedded in the winding *a*. The elastic material consists in this instance of a strip or strips *a*, Fig. 3, of rubber. It may, however, in some cases comprise elastic threads. The strips or threads *a* are wound spherically 50 under extreme tension around the hollow core or center B, whereby the said core or center becomes reduced in diameter, and the air or

other fluid it contains becomes considerably compressed. The contracted size or partial collapse of the soft-rubber shell D, due to the 55 tension of the rubber windings thereon, is indicated at D', Fig. 1, and it will be seen that the hollow D" is reduced in capacity as compared with the hollow of the original shell D, Fig. 2. It will be understood that the aggregate pressure to which the rubber shell is subjected by the multitude of tense rubber windings thereon is very great and that the shell consequently collapses until the pressure of the air, supplemented by the inherent 60 resistance of the shell itself, balances the contractile tendency or pressure of the rubber strips, thus producing a ball which flies a phenomenal distance when given a moderately-heavy blow. It will be understood that 70 the soft-rubber shell is depressible—that is, it can be indented.

The spherical shell *c* is constructed in halves or other sections, which when drawn together by the outer portion of the winding 75 inclose and compress the inner portion of the winding. When the outer portion of the winding has attained the diameter desired, the halves or hemispheres of the external casing or cover A are applied thereto and the 80 whole is given the usual treatment, whereby the casing or cover is caused to adhere firmly to the surface of the winding and the meeting edges of its halves or hemispheres are welded together. 85

It will be noticed that the hollow center piece *c* is provided with a hole C, through which it can, if desired, be inflated, said hole being after the inflation is effected hermetically closed in any suitable way. For example, the said center piece may be formed with a neck extending from said hole, and after the inflation of the center piece has been effected the neck may be closed by tying a stout cord around it, or a chemical substance 90 that will generate a gas when mixed with liquid may be placed into the center piece through its opening, and after the introduction of the liquid said hole may be sealed by vulcanization or otherwise, so as to hermetically inclose the contents. 95

What I claim, and desire to secure by Letters Patent of the United States, is—
1. In a playing-ball the combination of a

- hollow spherical center piece of soft elastic material filled with a gaseous fluid, a winding of highly-tensioned rubber exterior to said center piece, and a cover comprising cups 5 of a plastic material exterior to said winding, substantially as described.
2. In a playing-ball the combination of a pneumatic center piece, a winding thereon of elastic material under tension, a concentric 10 spherical shell of stiff springy material embedded in said winding, and an external cover, substantially as described.
3. In a playing-ball the combination of a pneumatic center piece, a winding thereon of 15 elastic material under tension, a plurality of concentric spherical shells of stiff springy material embedded in said winding, and an external cover, substantially as described.
4. In a playing-ball the combination of a 20 hollow spherical center piece inflated with air, a plurality of concentric windings of highly-tensioned rubber exterior to said center piece, a pair of hemispherical celluloid cups interposed between each winding and 25 the next, and an external cover comprising cups of gutta-percha, substantially as described.
5. In a playing-ball the combination of a hollow sphere of rubber constituting the center 30 piece and inflated with air, a plurality of spherical windings of highly-tensioned rubber exterior to said central sphere and concentric therewith, a pair of hemispherical celluloid cups interposed between each winding 35 and the next, and an external cover comprising cups of gutta-percha, substantially as described.
6. A playing-ball comprising a spherical rubber shell in a state of collapse, tense windings 40 of binding material thereon, and a shell of plastic material.
7. A playing-ball comprising a rubber sphere having a cavity and in a state of collapse, tense windings of rubber strip, and a cover of gutta-percha.
8. A playing-ball comprising a rubber sphere having a cavity and in a state of collapse, tense windings of rubber strip, a thin shell of celluloid, and a cover of gutta-percha.
- 50 9. A playing-ball comprising a compressible sphere of elastic material; tense windings thereon of extensible elastic material; said sphere being in a collapsed condition by reason of the contractile tendency of said windings; and a cover.
- 55 10. A playing-ball comprising a compressible sphere of soft rubber; tense windings thereon of extensible elastic bands, said sphere being in a collapsed condition by reason of the contractile tendency of said windings; and a cover.
- 60 11. A playing-ball comprising a compressible sphere of soft rubber; tense windings thereon
- of rubber bands, said sphere being in a collapsed condition by reason of the contractile 65 tendency of said windings; and a cover.
12. A playing-ball comprising a hollow sphere of soft rubber; tense windings thereon of extensible elastic material, said sphere being in a condition of partial collapse by reason of the contractile tendency of said windings, and containing elastic fluid under pressure; and a cover.
13. A playing-ball comprising a hollow sphere of soft rubber; tense windings thereon 75 of rubber bands, said sphere being in a condition of partial collapse by reason of the contractile tendency of said windings, and containing air under pressure; and a cover of hard plastic material.
14. A playing-ball comprising a hollow sphere of soft rubber; tense windings thereon of rubber bands, said sphere being in a condition of partial collapse by reason of the contractile tendency of said windings, and 85 containing air under pressure; and a cover of gutta-percha holding said windings under pressure.
15. A playing-ball comprising a compressible sphere of elastic material; tense windings 90 thereon of extensible elastic material, said sphere being in a collapsed condition by reason of the contractile tendency of said windings; a thin shell of stiff springy material embedded in said windings; and a cover.
16. A playing-ball comprising a compressible sphere of soft rubber; tense windings thereon of extensible elastic bands, said sphere being in a collapsed condition by reason of the contractile tendency of said windings; a thin 95 shell of celluloid embedded in said windings; and a cover.
17. A playing-ball comprising a hollow sphere of soft rubber; tense windings thereon of rubber bands, said sphere being in a condition of partial collapse by reason of the contractile tendency of said windings, and containing air under pressure; a thin shell 105 of stiff springy material embedded in said windings; and a cover of hard plastic material.
18. A playing-ball comprising a center piece having an air-cavity, tense windings thereon of highly-extensible elastic material, said center piece being partially collapsed 115 and the air therein being put under pressure by reason of the contractile tendency of said windings; and a cover.

In testimony whereof I have hereunto set my hand, in presence of two subscribing witnesses, this 29th day of September, 1902.

ELEAZER KEMPSHALL.
